UNITED STATES PATENT OFFICE

1,969,407

ELECTRICALLY LIGHTED TOY

Harry T. Kingsbury, Keene, N. H., assignor to
Kingsbury Manufacturing Company, Keene,
N. H., a corporation of New Hampshire

Application September 19, 1933, Serial No. 690,147

14 Claims. (Cl. 46—48)

The present invention relates to improvements in toys and more particularly to an electrically lighted toy which is provided with a handle device so that it may be pushed or pulled about by an operator.

An object of the present invention is to provide, in a toy of the type referred to, an improved handle device which is connected thereto and which consists of a plurality of sections whereby it may be folded.

Another object of the present invention is to provide, in a toy of the type referred to, an improved electric lighting system and a handle device having means thereon for opening and closing the electric lighting circuit.

A still further object of the present invention is to provide an improved toy, of the type referred to, which may be pushed along the floor by a child or other operator and which is strong and durable and thoroughly efficient in operation so that the lighting system may be turned on and off by the operator from the handle device.

These and other objects of the invention will in part be obvious and will be hereinafter more fully described.

In the drawing:

Fig. 1 is a side elevation of the assembled toy showing, in dotted lines, the manner in which the handle device may be folded.

Fig. 2 is a top plan view of the assembled toy with part of the handle broken away.

Fig. 3 is an enlarged bottom plan view of the body portion of the toy, partly in section.

Fig. 4 is an enlarged side view, in section, of the body portion of the toy.

Fig. 5 is a perspective view, in detail, showing the manner in which the two sections of the handle device are connected together.

The invention aims generally to provide a toy model of a wheeled vehicle which is provided with a handle device so that it may be pushed or pulled along a surface. The handle comprises two or more parts pivotally connected so that the entire handle may be folded in order to occupy less

space in shipping and storing of the toy. One or more electric lamps are mounted on the body portion of the toy and connected through suitable electric conductors to a dry cell battery which is also carried by the body portion of the toy. A suitable switch mechanism is also provided for opening or closing the electric light circuit and this switch mechanism is adapted to be conveniently controlled by the operator from a suitable operating device on the handle. In this man-

ner, a self-contained electrically illuminated toy is provided and one in which the illumination may be directly controlled from the handle of the toy.

Referring more in detail to the accompanying drawing, a toy vehicle in the form of a locomotive is shown for purposes of illustration, but it is to be understood that any toy model may be employed in connection with the present invention without departing from the scope thereof.

The toy 10 is, in the present embodiment of the invention, mounted on wheels 11, but it is to be understood that this is not an essential feature of the invention. A handle device 12 is connected to the toy so that it may be pushed or pulled about by an operator.

The toy 10 is preferably made of sheet metal, although this is not essential, and is provided with a chassis portion 13 through which extends an axle 14 on the ends of which the wheels 11 are mounted. A housing, which represents the locomotive cab, consists of an upright member 15, which is mounted on the chassis 13, and a cover member 16 mounted on the top of said upright member 15.

A hollow cylindrical member 17, which represents the boiler section of the toy locomotive, is secured to the upright member 15 and extends forwardly from an opening therein. A cap member 18 is secured over the front end of the cylindrical member 17 and is supported by a depending portion 19 which is mounted on the chassis 13.

The cap member 18 has a central opening 20 which is adapted to receive a lamp supporting socket 21 in which an electric light bulb 22 is supported. The cover member 16 of the housing carries a depending lamp supporting socket 23 which is also adapted to receive an electric light bulb 24.

On each side of the cylindrical member 17 is mounted a cylinder 25 within which a piston 26 reciprocates when the wheels rotate so that a more realistic appearance is given to the toy when in operation.

A disk 27, having a plurality of projections 28, is mounted on the axle 14. The projections 28 successively engage the free end of a metallic plate 29 through an opening 13a in the chassis when the axle rotates so that a clicking sound is produced as the toy is moved.

The top of the cylindrical member 17, at the forward part thereof, is punched in order to provide the upstanding pointed projections 30. A wooden plug 31, which represents the locomotive stack, is pushed over the projections 30 whereby it is properly secured in position.

The plug 31 has a depending portion 32, of lesser diameter, which extends below the under face of the cylindrical member 17.

100

105

110

A dry cell battery 33 is placed within the cylindrical member 17 and the rear end thereof is adapted to protrude slightly through the opening in the upright member 15 of the housing. A 5 bus-bar 34 is adapted to connect the terminals 22a, 24a of the light bulbs 22, 24 respectively to the battery terminal 35. The bus-bar 34 extends along the interior of the boiler member 17 between the boiler member and the battery and 10 has an opening 36, through which the depending portion 32 of the plug 31 passes. Small projections 37 around the opening 36 are embedded in the depending portion 32 so that the bus-bar is effectively supported. At the rear of the boiler 15 member 17 are two tabs 38 which are adapted to support a fiber insulating member 39, which, in turn, also supports the bus-bar 34. An insulating member 40 is placed between the bus-bar and the metallic boiler member 17 in order to prevent 20 any short-circuiting. The bus-bar 34 is bent upwardly adjacent the fiber member 39 and then at right angles within the housing. This end 41 of the bus-bar is then bent downwardly to provide a resilient contacting portion which engages the terminal 24a of the light bulb 24. The opposite end of the bus-bar is bent downwardly between the battery and the cap member 18. The extreme end 42 of the bus-bar is re-bent between the battery terminal 35 and the lamp terminal 22a so as to provide a resilient contact between 30 the battery terminal and the lamp terminal 22a.

The rear end of the chassis member 13 is provided with depending side skirt portions 43, 43a and upstanding corner post members 44, 44a. 35 The ends of the leg portions 45 of a spring member are secured to the chassis 13. The leg portions 45 lie flat against the under face of the chassis. The intermediate portion 46 of the spring member is bent to form a substantially U-shaped section which extends downwardly at an acute angle to the plane of the leg portions 45. A battery contact member 47 is provided with a central depending portion 48 which extends through an opening in the chassis and this portion 48 is provided with an opening through 45 which the portion 46 of the spring member passes. The contact member 47 is provided with two extensions 49, 50. The extension 49 passes through an opening in the chassis and engages the under face thereof in order to limit the clockwise movement of the contact member about the 50 spring portion 46 which serves as the pivot point. The other extension 50 has secured thereto a wire operating member 51 which extends along the handle device 12.

55 The handle device 12 is provided with a wire member 52 which is bent to form legs 53, 53a, the ends of which are secured in the skirt portions 43, 43a respectively of the chassis. The corner post members 44, 44a are provided with projecting portions 54, 54a. The legs 53, 53a of the wire member pass between the post members and under the projecting portions 54, 54a respectively thereof, so that the wire member is effectively secured to the chassis. The closed end of the 60 wire member passes through an opening in a wooden handle member 55 so that a pivotal connection is provided. A metallic plate 56 is secured over the lower end of the wooden handle member 55 by ears 57. The plate 56 is provided 65 with two notches 58, 58a in which the legs 53, 53a respectively of the wire member are snapped when the handle device is in an extended position, as shown in full lines in Figs. 1 and 3. The wire operating member 51 is provided with a 70 looped end 59 at approximately the point where 75

the wire member 52 is connected to the wooden handle member 55. A second wire operating member 60 is secured to a lever 61 which is pivotally mounted in the wooden handle member 55. This second wire member is also provided with a looped end 62 which is interlocked with looped end 59 of the wire member 51 and an intermediate portion passes through an eye 63.

80 It is thus apparent that, when the handle device is in the position shown in full lines in Fig. 1, the operator may push or pull the toy along the floor and may also open and close the electric lighting circuit at will by pressing the lever 61 with a finger. When the lever is pressed toward the handle member 55, the movement of the interlocked wire operating members 60, 51 will urge the contact member 47 toward and into contact with the battery 33 thus completing an electric circuit through the lamps 22, 24 so that they are lighted. When the lever 61 is released, the spring action of the spring portion 46 will urge the contact member 47 away from the battery and thus open the circuit and turn off the lights. The spring portion 46 urges the contact member 47 in a clockwise direction until part of 90 the extension 50 rests upon the chassis 13.

95 The handle device 12 is shown in a folded position by the dotted lines in Fig. 1. To accomplish this, the legs 53, 53a of the wire member 52 are forced out of the notches 58, 58a respectively and the handle member 55 is turned about the closed end of the wire 52 as a pivot. There is sufficient play in the interlocked looped ends 59, 62 of the operating wires 51, 60 respectively to permit the same to assume a position, shown in 100 dotted lines, without disconnecting them.

105 The nature and novel features of the present invention will be fully understood from the foregoing description. It is to be understood that minor details in construction and arrangement 110 of parts may be made without departing from the scope of the invention as set forth in the appended claims.

115 Having thus fully described my invention, what I claim as new and desire to secure by Letters 120 Patent, is:—

1. A toy comprising, in combination, a body portion, a light bulb, a battery, means for providing an electrical connection between said battery and said light bulb, a collapsible handle device secured to said body portion whereby the toy may be moved about, and switch means operable from said handle device for opening and closing the electric light circuit and collapsible with said handle device.

125 2. A toy comprising, in combination, a body portion, a light bulb, a battery, means for providing an electrical connection between said battery and said light bulb, a handle device secured to said body portion whereby the toy may be moved about, said handle device including a plurality of interengaging members whereby the same may be reduced in length, switch mechanism for opening and closing the electric light circuit, and means associated with said handle device for operating said switch mechanism, said last named means being reducible in length simultaneously with said handle device.

135 3. A toy comprising, in combination, a body portion, a battery carried by said body portion, a light bulb, means for providing an electrical connection between said battery and said light bulb, a handle device including a plurality of pivotally connected portions whereby said handle device may be folded, and means operable from one of 140

- said pivotally connected portions for opening and closing the electric light circuit and foldable with said handle device.
4. A toy comprising, in combination, a body portion, carrying a light bulb, a battery carried by said body portion, means for providing an electrical connection between said battery and said light bulb, a handle device secured to said body portion whereby the toy may be moved about, said handle device including a stationary member secured to said body portion and a handle member pivotally connected to said stationary member, a switch device for opening and closing the electric light circuit, and means operable from said handle device and including a plurality of links for operating said switch device. 80
5. A toy comprising, in combination, a body portion, electric light bulbs carried by said body portion at the opposite ends thereof, a battery mounted on said body portion, a bus-bar insulatedly supported on said body portion and extending from one light bulb terminal to the other, said bus-bar having resilient ends to contact the light bulb terminals, one of said ends being interposed between the battery terminal and a light bulb terminal, a handle device secured to said body portion whereby the toy may be moved about, and means operable from said handle device for opening and closing the electric light circuit. 85
- 20 6. A toy comprising, in combination, a body portion, a light bulb carried by said body portion, a battery supported by said body portion, means for providing an electric circuit connection between said light bulb and said battery, a spring member mounted on said body portion, a switch lever pivotally mounted on said spring member, a handle device connected to said body portion whereby the toy may be moved about, and means 90 on said handle device for operating said switch lever whereby to open or close the electric light circuit. 95
- 30 7. A toy comprising, in combination, a body portion, a light bulb supported by said body portion, a battery carried by said body portion, means for providing an electrical connection between the light bulb terminal and the battery terminal, a handle device whereby the toy may be moved about, said handle device including a U-shaped wire member having the leg portions thereof connected to said body portion, an upper handle member pivotally connected to the closed end of said wire member and securing means on said upper handle member for engaging the leg portions 100 of said wire member whereby to retain the handle member in extended position, said securing means being releasable to permit the handle device to be folded, and switch means operable from said upper handle member for opening and closing the electric light circuit. 105
- 40 8. A toy comprising, in combination, a body portion, a light bulb carried thereby, a battery supported by said body portion, means for providing an electrical connection between said light bulbs and said battery, a switch lever mounted on said body portion, a handle device for moving the toy and including a lower stationary member secured to said body portion and an upper member pivotally connected to said 110 lower member whereby the handle device may be folded, and means for operating said switch lever from said upper handle member whereby to open and close the electric light circuit, said last-named means including a finger lever pivotally secured to said upper handle member and a plurality of interconnected wire links joining said finger lever and said switch lever, said wire links being interconnected to permit the folding of said handle device. 115
- 25 9. A toy comprising in combination, a body portion carrying a light bulb, a battery carried by said body portion, means for providing an electric circuit connection between said light bulb and said battery, a handle device connected to said body portion whereby the toy may be moved about, a switch mechanism for opening and closing the electric circuit, means operable from said handle device for holding said switch mechanism in circuit closing position, and means including a resilient member on said body portion for normally holding said switch mechanism in circuit opening position. 120
- 35 10. A toy comprising, in combination, a body portion carrying a light bulb, a battery supported by said body portion, means for providing an electric circuit connection between said light bulb and said battery, a handle device connected to said body portion whereby the toy may be moved about, said handle device consisting of a plurality of foldable parts, and means operable from said handle device for opening and closing the electric circuit, said means including a plurality of interconnected elements foldable with said handle device. 125
- 40 11. A toy comprising, in combination, a body portion carrying a light bulb, a battery supported by said body portion, means for providing an electric circuit connection between said light bulb and said battery, a switch lever on said body portion for opening and closing the electric circuit, a handle device connected to said body portion whereby the toy may be moved about, said handle device consisting of a plurality of pivotally connected parts whereby the same may be folded, a finger lever pivotally secured to said handle device, and a connecting member between said finger lever and said switch lever whereby to operate said switch lever for opening and closing the electric circuit from the handle device, said connecting member being foldable with said handle device. 130
- 50 12. A toy comprising, in combination, a body portion carrying a light bulb, a battery supported by said body portion, means for providing an electric circuit connection between said battery and said light bulb, a handle device including a U-shaped member having the leg portions thereof connected to said body portion and a handle member pivotally connected to the closed end of said U-shaped member, a switch lever pivotally mounted on said body portion and adapted to open and close the electric circuit, and means operable from said handle member for operating said switch lever, said last-named means including a lower wire member loosely connected to 135 said switch lever and an upper wire member interconnected at one end with said lower wire member and connected at the opposite end to a finger lever on said handle member, the interconnected ends of said wire members being adapted to pass between the leg portions of said U-shaped member whereby to permit the handle device to be folded. 140
- 55 13. A toy comprising, in combination, a body portion, a light bulb supported by said body portion, a battery carried by said body portion, means for providing an electrical connection between said light bulb and said battery, a handle device whereby the toy may be moved about, said handle device including a U-shaped wire 145 member pivotally connected to said body portion, a switch lever pivotally secured to said handle device, and means for operating said switch lever from said upper handle member whereby to open and close the electric light circuit, said last-named means including a finger lever pivotally secured to said upper handle member and a

14. A toy comprising in combination, a body
